UNITED STATES PATENT OFFICE.

JOHN H. COX, OF HOT SPRINGS, ARKANSAS.

CAR-REPLACER.

1,206,993.

Specification of Letters Patent.

Patented Dec. 5, 1916.

Application filed March 10, 1915. Serial No. 13,408.

To all whom it may concern:

Be it known that I, JOHN H. Cox, citizen of the United States, residing at Hot Springs, in the county of Garland and State 5 of Arkansas, have invented certain new and useful Improvements in Car-Replacers, of which the following is a specification:

My invention relates to improvements in portable frogs or "car replacers."

10 The primary object of the invention is to replace on the track derailed cars or railway rolling stock, although the device may be equally as well used to derail a car, where required.

15 A further object of the invention is to strengthen and stiffen the construction whereby the frog may be made out of a single metal casting, thereby procuring greater lightness for convenient handling 20 and greater economy in the cost of the material used in the manufacture of the frog.

25 A still further object is to improve on the details of construction in various ways, which will be fully described, and pointed out in the claims.

I accomplish the objects of the invention by the mechanism illustrated in the accompanying drawings, in which:—

30 Figure 1 is a top plan view of my improved portable frog or car replacer; Fig. 2 is an inverted plan view; Fig. 3 is an end view; and Fig. 4 is a cross section on the line 4—4 of Fig. 1.

Like characters of reference indicate like 35 parts throughout the several views of the drawings.

It is to be understood that in derailing or replacing a car, two frogs are required, and inasmuch as the two frogs forming a 40 pair differ from each other only in having their parts in reverse order to each other, a description of one will suffice for both.

In its preferred embodiment, the entire frog or replacer is constructed of a single 45 metal casting which, as pointed out above, will economize in material used and will strengthen materially the entire device. Said casting, designated as an entirety by the numeral 1 may be said to comprise a 50 somewhat elongated body 2 diverging from a point intermediate the frog terminals toward either end.

The top face of the frog is of a tapering 55 formation, and from a side elevation, may be said to be arched-shape, although the thickness in the center is considerably

greater than the thickness at the respective ends. The under side of the frog 1 is cut away transversely as indicated at 3 to lessen the material used in its construction and to 60 form, at the opposite ends of the frog, enlargements or projections 4 which are adapted for engagement with the railway tie or the filling therebetween. To further increase the lightness of the frog as well as to further 65 economize in the material used, the enlargement 4 may be longitudinally grooved or cut away as indicated at 5, each rib-like enlargement thus formed being serrated to create a biting contact with the tie. The 70 teeth thus formed, and for clearness designated as 6 are so constructed as to extend transversely of the frog and at an angle to the transverse line, the total number of teeth affording an anti-slipping means to preclude 75 longitudinal movement of the frog when in use and during a replacing or derailing operation.

To prevent lateral displacement of the frog when in use, I provide a longitudinal 80 groove 7 within which the railway rail 8 is seated, the said groove 7 being of a sufficient depth to expose the tread of the rail 8 to view throughout a portion of its length beyond the outer extremities of the frog, such 85 construction and arrangement, by reason of the tapering terminals, allowing the periphery of the car wheel to ride onto the tread of the rail as it follows the guide grooves therefor created by the frog formation, as 90 will hereinafter appear.

At each side of the central longitudinal groove 7, the under face of the frog is tapered or cut at an inclination, as indicated at 9 to rest upon the similarly inclined top 95 face of the base flange of the rail. The top face of the frog is provided with a central groove 10, the said groove being of a width and depth to receive freely the flange of the car wheel and leading from one end of 100 the frog to a point adjacent said end where it is diverged, as indicated at 11, the diverged extremity of the groove being subdivided through the medium of ribs 12 to 105 create in substance a plurality of converging grooves 13, each leading to the single groove 10 upwardly from the opposite end of the frog over the arched upper surface thereof to the point 11 aforesaid. The ribs 12 afford a riding surface for the car wheel 110 and direct the said wheel, during a car replacing operation, to the common groove 10,

which, by reason of its disposition relatively to the rail 8, directs the periphery of said wheel onto the tread of the rail, the flange of the wheel being directed, by a continuation of the groove to the inside edge of the rail as required.

It will be noted that the central dividing rib 12 is somewhat larger than the remaining ribs, the said rib, by reason of such enlargement, strengthening the frog centrally or at a point that would otherwise be materially weakened by reason of its formation upon the under side. By diverging the frog at the end from whence the several grooves 13 lead, it is evident that an extended area is in effect and that a car may be replaced readily and easily so long as the wheel is directed to the frog and to one or the other of the several grooves 13 thereon.

10 The body 1 of the frog is vertically extended or enlarged, as indicated at 12, adjacent the outside edge of the groove 10 (that is, outside with respect to the rail 8) thereby affording an abutment surface for the flange and positively precluding derailment subsequent to movement of the car onto the frog and onto the inclined top surface thereof which leads to the rail. If desired, should the teeth 6 prove inadequate, the frog may be fastened as indicated at 13' to the cross ties. When not in use, the frog may be hung or suspended from any suitable support, openings 14 being provided for that purpose.

15 35 From the foregoing, taken in connection with the accompanying drawings it is evident that an effective frog is produced from a single metal casting, the novel construction facilitating displacement or derailment as hereinbefore pointed out; that longitudinal movement of the frog relatively to the rail in connection with which it is used is precluded by reason of the biting engagement of the teeth 6 with the tie and the filling substance therebetween; and that the arched formation of the device as a whole is such

in its nature as to aid and direct movement of the car wheel either from or onto the rail as occasion may demand.

In reduction to practice, I have found 50 that the form of my invention, illustrated in the drawings and referred to in the above description, as the preferred embodiment, is the most efficient and practical; yet realizing that the conditions concurrent with the 55 adoption of my device will necessarily vary, I desire to emphasize the fact that various minor changes in details of construction, proportion and arrangement of parts may be resorted to, when required, without sacrificing 60 any of the advantages of my invention, as defined in the appended claims.

Having thus fully described my invention, what I claim as new and desire to secure by Letters Patent, is:—

65 A car replacer comprising a casting of arched formation, having a longitudinal groove in its under face adapted to receive the rail, and inwardly extending recesses at the ends of the groove through which the 70 head of the rail is exposed, said casting also having a longitudinal major groove in its upper face extended across the entire width of the casting at one end and converging toward the other end to a groove having 75 approximately the width of the rail head, said narrow portion being disposed to one side of the recess, a ridge formed centrally of the groove at the widened portion and converging toward the narrow portion, and 80 a plurality of ridges formed between the central ridge and the sides of the groove to define a plurality of minor grooves merging into the narrow portion of the major groove.

85 In testimony whereof I affix my signature in presence of two witnesses.

JOHN H. COX.
